BALANCING TOY DOLL

Walter Hampton Vestal, 820 Silver Ave.,
Greensboro, N.C.

Filed Dec. 13, 1961, Ser. No. 67,897

Term of patent 14 years

(Cl. D34—15)

FIG. 1

FIG. 3

FIG. 1 is a front perspective view of a balancing toy doll showing my new design;

FIG. 2 is an enlarged front elevational view of the balancing toy doll of FIG. 1 with the projecting balancing members shown fragmentarily for convenience of illustration; and

FIG. 3 is a right side elevational view of FIG. 2.

The broken line showing of a rope in FIG. 1 is for illustrative purposes only.

What I claim is:

The ornamental design for a balancing toy doll, as shown and described.
